UNITED STATES PATENT OFFICE.

MARTIN KROSCHEINSKY, OF BALTIMORE, MARYLAND, ASSIGNOR TO MARKEB MANUFACTURING COMPANY, OF BALTIMORE, MARYLAND, A CORPORATION OF MARYLAND.

METALLIC PISTON-PACKING RING.

Application filed March 11, 1922. Serial No. 542,960.

To all whom it may concern:

Be it known that I, MARTIN KROSCHEINSKY, a citizen of the United States, residing in the city of Baltimore, State of Maryland, 5 have invented certain new and useful Improvements in Metallic Piston-Packing Rings; and I do hereby declare the following to be a full, clear, and exact description of the invention, such as will enable others 10 skilled in the art to which it appertains to make and use the same.

My present invention relates to improvements in metallic piston packing rings, and it consists in providing a ring composed of 15 two members, that is, an inner and an outer ring so constructed and arranged that the tendency of the composite ring when in use on the piston in the cylinder will tend to always make a tight joint between the interior 20 of the cylinder and the piston.

The invention is also intended to provide a packing ring which may be easily installed without breakage; a ring which will work 25 equally well when in the inverted position; a ring that does not require joint spacing to secure maximum results, and a ring which braces its own circle by having its breaks or joints spaced at approximately 125 degrees apart in its construction.

According to my invention the inner ring 30 is made in the form of an inverted L, in cross section, and the outer ring fits snugly beneath the radial flange of the L and is tied to the outer ring by means of a suitable pin 35 or other engagement at a distance of approximately 125° from the break in the inner ring. Thus the breaks in the inner and outer rings are spaced substantially 125° apart. By this arrangement the elasticity 40 of the composite ring will be such that all parts of the ring will tend to form a tight joint as before described.

My invention will be more fully understood after reference to the accompanying 45 drawings, in which like parts are indicated by similar reference symbols throughout the several views, and in which:—

Figure 1 is a perspective view of the complete packing ring in the assembled relation, 50 but before being compressed to fit in the cylinder.

Figure 2 is a similar view, but shows the two rings both compressed until the split ends of each ring abut.

Figure 3 is a plan view of the two rings 55 as shown in Fig. 1, parts of the outer ring being broken away to show the positioning pin.

Figure 4 is a plan view showing the two rings separated, and parts being broken 60 away.

Figure 5 is a perspective view showing the inner ring detached.

Figure 6 is a perspective view of the outer ring. 65

Figure 7 shows a section along the line 7—7 of Fig. 3, and looking in the direction of the arrows, the parts being shown on a larger scale than in Fig. 3; and

Figure 8 is a similar view to Fig. 7, but 70 shows a modification in which the positioning pin is parallel to the axis of the ring, and not radial to said axis, as shown in Figs. 3 and 7.

A represents the inner ring which is substantially in cross section in the form of an inverted L, with the flange a' uppermost, and the web a mounted in the grooves, not shown, on the piston. Between the two ends of the ring A is the usual opening a°. 75

B represents the outer ring which is substantially rectangular in cross section, and has its two ends shaped to form overlapping tongues b and b' beyond the shoulders b² and b³. The tongue b', is of greater 80 length than the tongue b, so as to provide, at the split of the ring B, a permanent gap at one side of the meeting ends of the ring B, when the ends of the latter are in abutting engagement. This outer ring B is preferably peened on its inner face opposite the break, as indicated at b⁴, to give it tension. 85

In order to prevent one ring from creeping around relative to the other when in use in the engine, I provide a positioning pin 95 C fast to the inner ring A, which pin projects into the gap in the ring B. This pin may be radially disposed relative to the ring A, as shown in Figs. 1 to 5, and Fig. 7, or it may be parallel to the axis of the ring A, as shown in Fig. 8.

By either construction only a small cir-

cumferential play of one ring relative to the other is permitted, and the breaks in the inner and outer rings, when in use as a metallic packing, will always be held by the pin C substantially the predetermined angular distance apart.

I have found that by permanently maintaining the angular distance of about 125° between the breaks in the two rings very substantial advantages are secured; thus an irregular expansive tendency of the complete ring is prevented and the expansive tendency made substantially uniform throughout, and a tight joint all around is effected both between the outer ring and the cylinder wall, and between the two rings where their circumferences press together radially.

It will be noted that the two rings A and B may be quickly and conveniently assembled to form a composite ring, and will remain locked together against relative circumferential movement, while still extensible.

It will also be noted that the outer ring B is protected from carbon by the overlapping edge a' of the inner ring; while the wear is mainly taken on the thicker outer ring B, thus materially increasing the life of the device.

Moreover by the herein described arrangement the amount of metal in each of the rings A and B is sufficient, with the construction shown, to prevent accidental

breakage of either ring even until both are 35 badly worn.

Various other advantages of the herein described packing will readily suggest themselves to those skilled in the art.

Both members of the compound ring are 40 preferably made of gray cast iron, and are soft and flexible.

It will be obvious that various modifications might be made in the herein described construction, and in the combination and arrangement of parts which could be used without departing from the spirit of my invention; and I do not mean to limit the invention to such details except as particularly pointed out in the claim.

Having thus described my invention what I claim and desire to secure by Letters Patent of the United States is:—

A compound metallic packing comprising an inner and outer separate compressible split ring, the splits in said rings spaced relatively to each other at an angular distance of substantially 125 degrees apart circumferentially in one direction, and a radially disposed pin carried by and projecting from the inner ring and extended into the gap of the outer ring to arrest circumferential movement of one ring relatively to the other and further for permanently maintaining the splits of the rings spaced 60 apart a distance of substantially 125 degrees.

MARTIN KROSCHINSKY.
